Patented Dec. 7, 1920.

2 SHEETS—SHEET 2.

UNITED STATES PATENT OFFICE.

HERMAN R. SAXON AND GEORGE GANZERT, OF TOLEDO, OHIO, ASSIGNEES, BY MESNE ASSIGNMENTS, TO INDUSTRIAL RESEARCH CORPORATION, OF TOLEDO, OHIO, A CORPORATION OF DELAWARE.

FUEL-FEEDING DEVICE.

1,361,621.

Specification of Letters Patent.

Patented Dec. 7, 1920.

Application filed June 11, 1917. Serial No. 174,108.

To all whom it may concern:

Be it known that we, HERMAN R. SAXON and GEORGE GANZERT, citizens of the United States, residing at Toledo, in the county of Lucas and State of Ohio, have invented certain new and useful Improvements in Fuel-Feeding Devices, of which we declare the following to be a full, clear, and exact description.

10 This invention relates to improvements in fuel feeding devices for automobiles, of the type embodied in our co-pending application filed June 11, 1918, Serial Number 174107. The present invention relates particularly to devices of the type which are operated by the suction existing in the intake manifold of the engine, when running, to lift fuel from a main fuel tank to an auxiliary vacuum tank, from which the fuel 20 feeds to the carbureter.

25 The principal object of our invention is to provide an improved valve action for controlling the connections between the vacuum tank and the atmosphere and the source of suction. A further object of our invention is to provide an improved vacuum tank construction, of such a nature that it can be produced in large quantities at a low cost and can be readily and conveniently assembled.

30 Further objects, and objects relating to economies of manufacture and details of construction, will definitely appear from the detailed description to follow.

35 We accomplish the objects of our invention by the devices and means described in the following specification. Our invention is clearly defined and pointed out in the appended claims.

40 A structure constituting a preferred embodiment of our invention is illustrated in the accompanying drawing, forming a part of this specification, in which:

45 Figure I is a diagrammatic view of our improved vacuum tank, connected to the main fuel tank, the engine and the carbureter.

50 Fig. II is a vertical, sectional view through a vacuum tank constructed in accordance with our invention.

Fig. III is a fragmentary view, partly in section and partly in side elevation, showing the valve mechanism with the valve in position opening the connection with the at-

mosphere and closing the connection with the suction means.

Fig. IV is a fragmentary view in side elevation, of a portion of the valve operating mechanism, with the valve in position opening the suction means and closing the connection with the atmosphere.

Fig. V is a fragmentary view, similar to Fig. IV but showing the valve mechanism in the position shown in Fig. III.

Fig. VI is a detail, sectional view, taken substantially on the line VI—VI of Fig. II.

Fig. VII is a vertical, sectional view taken through a vacuum tank embodying a modified form of our invention.

Fig. VIII is a view in side elevation showing the valve operating mechanism.

Fig. IX is a vertical, sectional view, taken substantially on the line IX—IX of Fig. VIII.

In the drawings, similar reference numerals refer to similar parts throughout the several views, and the sectional views are taken looking in the direction of the little arrows at the ends of the section lines.

Considering the numbered parts of the drawings, it will be seen that our fuel feeding system comprises a vacuum tank 10, which is connected by the conduit 14 with the main fuel supply tank 13. The vacuum tank is connected with the intake of the engine 15, preferably at a point between the carbureter and the intake manifold, by means of a suction conduit 16, and is also connected with the carbureter 17, by means of the fuel supply conduit 18.

Our vacuum tank comprises a float chamber 19, and an auxiliary chamber 20, from which the fuel feeds by gravity to the carbureter. The diameter of the auxiliary chamber 20 is slightly less than that of the float chamber 19, and said chamber 20 is provided at its open upper end with the laterally extending figure 23, on which is disposed the gasket 24, on top of which rests the bottom of the main float chamber 19, as clearly appears from Fig. II of the drawing. The main float chamber is provided with a cover 25, there being a gasket 26 interposed between the top flange of the chamber 19 and the cover 25. The stem 27 is disposed axially of the chamber 19, with its ends extending through the bottom thereof and through the cover 25, both of said ends

being threaded, the elbow 28, connected to the suction conduit 16, being screwed on to the upper threaded end of said stem, as appears from Fig. II. A T-coupling 29 is 5 screwed on to the threaded lower end of the stem 27, below the bottom of the chamber 19. Nut 30 is screwed on to said threaded lower end of stem 27, above the bottom of the chamber 19, so that the bottom of the chamber 10 is securely clamped between the nut 30 and the T-coupling 29. Stem 33 is threaded into the lower end of the T-coupling 29, the lower end of said stem extending through the bottom of the auxiliary chamber 20, and 15 the elbow 34, which is connected by the conduit 18 with the carbureter 17, is threaded on to the lower end of the stem 33, outside of the bottom of the auxiliary chamber 20. Stud 35 extends through the cover 25 and 20 the elbow 36 is threaded on to the upper end of said stud, to which elbow the fuel supply conduit 14 is connected.

Passages 37 and 39 are provided in the upper end of the stem 27, the lower entrance 25 to each of said passages being through the side of the stem, as appears from Fig. II of the drawing. Opening 38 is provided in the side of the elbow 28, in position to be aligned with the upper end of the passage 30 39, as appears from Fig. II. It will be seen that by means of these passages, a connection may be made between the chamber 19 and the suction means, or between the chamber 19 and the atmosphere. A passage 35 40 is provided in the stud 35, through which fuel is delivered from the fuel supply passage 14 to the main float chamber 19.

The sleeve valve 43 is slidably mounted on the stem 27 and provided with the lower 40 flange 44, and the upper flange 45. A stop pin 46 is carried by the upper end of stem 27, in position to limit the upward movement of the sleeve valve 43. The entrances to the passages 37 and 39 are so disposed 45 and spaced relative to each other, that said sleeve valve 43 will, in its lower position, cover the entrance to the passage 39, and, in its upper position, will cover the entrance to the passage 37.

50 Float 47 is provided with a central opening therein, in which are fixed the upper flange 48 and the lower flange 49, which form a bearing for the float on the stem 27, said flanges being connected together by the 55 bolts 50 passing through the flanges and the float. A slot 53 is provided in the lower end of the stud 35, and lever arms 54, the main parts of which extend on opposite sides of the stem 27, have their outer ends 60 bent toward each other and disposed in the slot 53, being secured therein by pivot pin 55 passing through the stud 35 and through the ends of said lever arms 54. The ends of said lever arms are provided with the 65 openings 56, and hooks 57, are secured to

the flange 48 of the float, at diametrically opposite points thereon, said hooks having the laterally turned portions 58, which are disposed within the said openings 56. The levers 54 carry the laterally extending pins 70 59, and a stud 60 is secured to the cover 25 and extends downwardly within the float chamber, said stud carrying a laterally extending pin 63. Springs 64 are connected at one end to the pin 63, and at the other 75 end to one of the pins 59 carried by the lever arms 54. A transverse passage 65 is provided in the lower end of the stem 27 and communicates with an axial passage 66 and the passage 67 formed in the T-coupling 80 29. The nipple 68 is screwed into the horizontal arm of the coupling 29 and provided with a passage 69 so that fuel may flow from the float chamber through the passages 65, 67 and 69 to the auxiliary chamber. 85

A ball 70 is disposed in the passage 67, forming a non-return valve permitting the fuel to flow from the float chamber 19 to the auxiliary chamber 20, but preventing the flow of the fuel in the opposite direction. 90 A stem 33 is screwed into the lower end of the T-coupling 29 and provided with a transverse passage 73 and an axial passage 74, communicating with the nipple 34, to which is connected the fuel supply passage 95 18 leading to the carbureter, so that fuel may flow from the chamber 20 through the passages 73 and 74 to the conduit 18.

A vent tube 75 is disposed within the chamber 19, the lower end of said vent tube 100 being connected with the opening 76, in the bottom of the chamber 19, and the upper end of said vent tube, being connected with the opening 77, in the side wall of the chamber 19, near the top thereof, so that the auxiliary chamber 20 is always maintained under atmospheric pressure and fuel will flow therefrom by gravity to the carbureter at all times. 105

The embodiment of our invention shown 110 in Figs. VII, VIII and IX is the same in all its essential particulars, as that shown in Figs. I to VI inclusive, with the exception that, in this embodiment of our invention, we do not employ an auxiliary chamber 20 from which the fuel flows to the carbureter. A small vent 86 is provided in the cover 25, which vent is considerably smaller than the passage 37 by means of which the chamber 19 is connected with the 115 suction means, and, in this form of our invention, the chamber 19, is continuously open to the atmosphere through the small vent 86. The elbow 78 is screwed on to the lower end of the stem 27 and provided with 120 a passage 79 therein. The elbow carries the nipple 83, connected to the conduit 18 leading to the carbureter, and a ball valve 84 is disposed in the passage 79, and is adapted to contact with or seat in the restricted por- 125 130

tion 85 of the passage 79, permitting fuel to flow from the chamber 19, but preventing any flow in the opposite direction. A removable plug 80 is provided in the elbow 78, through which the fuel may be drained therefrom and access may be had to the valve seat in order to clear the same. It will be obvious that, in this form of our invention, the vent tube is not needed and 10 for that reason it is omitted. In other respects, this form of our invention is the same as shown in Figs. I to VI inclusive.

From the description of the parts given above, the operation of our device should 15 be very readily understood. In assembling the parts of the vacuum tank, the chambers 19 and 20 are formed separately and a stem 33, with the T-coupling 29 attached thereto is inserted through the opening in the bottom 20 of the auxiliary chamber 20, and the elbow 34 is screwed on to the lower end of the stem 33. The main float chamber 19 is then seated with its bottom resting on the gasket 24, carried by the flange 23, of the auxiliary chamber 20 and the stem 27 is inserted through the opening in the bottom of the chamber 19 and threaded into the T-coupling 29, the nut 30 being tightened to clamp the bottom of the chamber 19, between the end of the T-coupling 29 and the nut 30. This draws the bottom of the chamber 19 into tight fitting engagement with the gasket 24, so that the chambers 19 and 20 are firmly secured together. The float 47 is placed on the stem 27 and the cover is placed on the chamber 19, the sleeve 43 being slipped over the stem 27, after which the pin 46 is inserted, to prevent the removal of the valve operating mechanism. The elbows 28 and 36 are then screwed on to the upper ends of the stem 27 and the stud 35, respectively and these serve to hold the cover 25 in tight fitting engagement with the top edge of the chamber 19. The elbow 28 is connected with the intake manifold of the engine 15 by the conduit 16, as has already been described, and the chamber is always in communication with the main fuel tank 13, through the conduit 14, which opens into 45 the passage 40 in the stud 35. When the parts are in the position shown in Fig. II of the drawing, chamber 19 is in communication with the intake manifold of the engine and closed to the atmosphere, since the sleeve valve 43 closes the lower end of the 50 passage 39 which connects with the atmosphere and forms an air vent for the chamber 19. Suction existing in the intake manifold of the engine will thus cause a partial 55 vacuum in the chamber 19 and, since the fuel in the main fuel tank 13 is under atmospheric pressure, the fuel will be lifted through the conduit 14 and flow through the 60 passage 40 into the chamber 19. As the fuel 65 flows into the chamber 19, the float 47 will

of course be lifted. When the float has risen a predetermined distance, the laterally turned ends 58 of the hooks 57, engage the upper edges of the openings 56, in the heads of the lever arms 54, and swing said levers upward on their pivot 55, carrying the springs 64 from the position shown in Fig. IV to that shown in Fig. V and lifting the sleeve valve 43 so that it uncovers the lower end of the passage 39 and covers the lower end of the passage 37. In that case, the chamber will be placed in communication with the atmosphere through the port 38 and will be closed to the suction means since the passage 37 is closed. It will be seen that, in the position shown in Fig. IV, the sleeve valve is held in its lower position, the springs 64 tending to draw the levers 54 downwardly, while, when the springs are in the position shown in Fig. V, they tend to draw the levers 54 upwardly and hold the sleeve valve in engagement with the stop pin 46. The openings 56 are quite large so that there will be a considerable movement of the float 47 without affecting the lever arms to throw them from one position to the other. By this means, we secure an intermittent action of the valve operating mechanism due to the rising and falling of the float as the fuel is intermittently fed into the chamber 19 and fed from the chamber 19 to the auxiliary chamber 20.

When the sleeve valve is in the position shown in Fig. III, atmospheric pressure exists in the chamber 19, and hence fuel will no longer flow from the main fuel tank into the float chamber. As atmospheric pressure is restored in the float chamber 19, the fuel therein will flow by gravity past the check valve formed by the ball 70 to the auxiliary chamber 20, so that, when the suction is cut off, the atmospheric pressure exists in the float chamber 19, the fuel flows naturally into the auxiliary chamber 20 to maintain the supply therein. After the fuel has fed from the float chamber 19 sufficiently to permit the float to drop a predetermined distance, the ends 58 of the hooks 57 engage the lower edges of the openings 56, and throw the lever arms from the position shown in Fig. V to the position shown in Fig. IV, thus bringing the sleeve valve 43 to its lower position, connecting the chamber with the suction means and cutting it off from the atmosphere.

The auxiliary chamber 20 is always maintained under atmospheric pressure due to the vent tube 75 which connects the chamber 20 with the atmosphere, the upper end of said vent tube being always above the level of the fuel in the float chamber 19, and hence fuel will flow by gravity as needed from the auxiliary chamber 20 to the carbureter.

In Figs. VII, VIII and IX we have shown

another modification of our invention which is substantially the same as that shown in Figs. I to VI except that the auxiliary chamber 20 is omitted, the valve operating mechanism being the same in both cases. A small vent 86 is provided in the cover 25 and this vent is much smaller than the port 37 connecting the chamber with the suction means so that air can not enter the chamber through the port 86 as fast as it is taken from the chamber by the suction means through the port 37. Since the chamber 19 is not always maintained under atmospheric pressure, but sometimes has a partial 15 vacuum therein, the fuel will not flow continuously from the chamber 19 to the carburetor, but there will be an intermittent flow to the carburetor from this chamber whenever the suction is cut off and atmospheric pressure is restored in the chamber. 20 This arrangement may serve in some cases, although it is not as desirable as the preferred construction.

We have found that the particular embodiment of our invention, which we have here shown and described, is desirable from many standpoints, but we are aware that it may be varied considerably, without departing from the spirit of our invention, 30 and we, therefore, do not wish to be limited to the exact construction shown.

Having thus described our invention, what we claim as new and desire to secure by Letters Patent is:—

35 1. In a device of the class described, the combination of a tank having independent and separate connections with a supply of fuel, a source of suction and the atmosphere; a sleeve valve controlling the last two connections; and means for actuating said sleeve valve.

40 2. In a device of the class described, the combination of a tank having independent and separate connections with a supply of fuel, a source of suction and the atmosphere; a float in said tank; a sleeve valve for controlling the last two connections; and float-actuated means for operating said sleeve valve.

45 3. In a device of the class described, the combination of a tank having independent and separate connections with a supply of fuel, a source of suction and the atmosphere; a sleeve valve for controlling the last two connections; and intermittently operating means for actuating said sleeve valve.

50 4. In a device of the class described, the combination of a tank having independent and separate connections with a supply of fuel, a source of suction and the atmosphere; a sleeve valve for controlling the last two connections, said sleeve valve in one position, closing the connection with the source of suction and opening the connection with the atmosphere, and, in another position, clos-

ing the connection with the atmosphere and opening the connection with the source of suction; and float for intermittently actuating said sleeve valve from one position to the other.

5. In a device of the class described, the combination of a tank; a stem disposed in said tank; passages in said stem connecting said tank with a source of suction and the atmosphere respectively; and spring-controlled float actuated valve means for alternately closing and opening said connections to establish connection with said suction source and to close said tank against atmospheric pressure.

6. In a device of the class described, the combination of a tank; a stem disposed in said tank, and provided with passages therein connecting said tank with a source of suction and the atmosphere respectively; a sleeve valve mounted on said stem and controlling said passages; and a float for actuating said sleeve valve to alternately place the tank into communication with said suction source and to close it against atmospheric pressure.

7. In a device of the class described, the combination of a tank; a stem disposed in said tank, and provided with passages connecting said tank with the atmosphere and a source of suction respectively; a sleeve valve slidably mounted on said stem, and controlling said passages to alternately place the tank in communication with the atmosphere and said suction source; a float slidably mounted on said stem; and connections between said float and said sleeve valve whereby said sleeve valve is intermittently actuated by the rise and fall of said float.

8. In a device of the class described, the combination of a tank; a stem disposed in said tank, having separate and independent passages connecting said tank with the atmosphere and a source of suction respectively; a float slidably mounted on said stem; a sleeve valve slidably mounted on said stem, and having a pair of flanges; a tube carried by said tank, and having a passage connected with a supply of fuel; levers fulcrumed on said tube, and extending on either side of said stem, said levers having enlarged openings in the free ends thereof, and carrying transverse pins adapted to engage the flanges of said sleeve valve; hooks carried by said float and having laterally turned ends disposed in said openings; a stud carried by said tank, and having a transverse pin; springs connected with said pin and the pins on said levers; and a one-way connection leading from said tank.

9. In a device of the class described, the combination of a tank; a stem disposed in said tank and having passages connecting said tank with the atmosphere and a source

- of suction respectively; a float slidably mounted on said stem; a sleeve valve slidably mounted on said stem, and having a pair of flanges; a tube carried by said tank 5 and having a passage connected with a supply of fuel; levers fulcrumed on said tube, and extending on either side of said stem, said levers having enlarged openings in the free ends thereof, and carrying transverse 10 pins adapted to engage the flanges of said sleeve valve; hooks carried by said float and having laterally turned ends disposed in said openings; a stud carried by said tank, and having a transverse pin; springs connected with said pin and the pins on said levers; and a one-way connection leading from said tank.
10. In a device of the class described, the combination of a tank; a stem disposed in 20 said tank and having passages connecting said tank with the atmosphere and a source of suction respectively; a float slidably mounted on said stem; a sleeve valve slidably mounted on said stem, and having a 25 pair of flanges; a stud carried by the top of said tank and having a passage connected with a supply of fuel; levers fulcrumed in said stud and extending on either side of said stem, said levers having enlarged openings in the free ends thereof, and carrying transverse pins adapted to engage the flanges of said sleeve valve; and hooks carried by said float, having laterally turned ends disposed in said openings.
35. 11. In a device of the class described, the combination of a tank; a stem disposed in the tank and having passages connecting said tank with the atmosphere and a source of suction respectively; a fuel supply connection for said tank; a float slidably mounted on said stem; a sleeve valve slidably mounted on said stem and having a pair of flanges; suitably fulcrumed levers extending on either side of said stem, said levers 40 having enlarged openings in the free ends thereof, and carrying transverse pins adapted to engage the flanges of said sleeve valve; hooks carried by said float and having laterally turned ends disposed in said openings; 45 and a one-way connection leading from said tank.
12. In a device of the class described, the combination of a tank; a stem disposed in said tank and having passages connecting said tank with the atmosphere and a source of suction respectively; a fuel supply connection for said tank; a float slidably mounted on said stem; a sleeve valve slidably mounted on said stem and having a pair of flanges; suitably fulcrumed levers extending 55 on either side of said stem, said levers having enlarged openings therein and transverse pins adapted to engage the flanges of said sleeve valve; connections between said 60 float and said levers, movable in said open- ings to permit a limited movement of the float in either direction without affecting said lever; and a one-way connection leading from said tank.
13. In a device of the class described, the combination of a tank; a stem disposed in said tank, and having passages connecting said tank with the atmosphere and a source of suction respectively; a float slidably mounted on said stem; a sleeve valve slidably mounted on said stem; suitably fulcrumed levers extending on either side of said stem; connections between said levers and said sleeve valve and between said levers and said float, said last-named connections being such as to permit a limited movement of the float without affecting said levers; and a one-way connection leading from said tank.
14. In a device of the class described, the combination of a tank; a stem disposed in said tank and having passages connecting said tank with the atmosphere and source of suction respectively; a fuel supply connection for said tank; a float in said tank; a sleeve valve slidably mounted on said stem and controlling said passages; spring controlled connections between said float and said valve, said connections being such as to permit of a limited movement of the float 95 without affecting the valve; and a one-way connection leading from said tank.
15. In a device of the class described, the combination of a tank; a stem disposed in said tank and having passages connecting said tank with the atmosphere and a source of suction respectively; a fuel supply connection for said tank; a float in said tank; a sleeve valve slidably mounted on said stem and controlling said passages; a suitably 100 fulcrumed lever; connections between said lever and said sleeve valve and between said lever and said float of such a nature as to permit of a limited movement of said float 105 without affecting said lever; and a one-way connection leading from said tank.
16. In a device of the class described, the combination of a tank; a stem disposed in said tank, and having passages connecting said tank with the atmosphere and a source of suction respectively; a fuel supply connection for said tank; a float disposed in said tank; a sleeve valve slidably mounted on said stem; a fulcrumed lever in said tank, said lever having an enlarged opening in the free end thereof; a connection between said lever and said sleeve valve; and an upwardly extending arm carried by said float and having a laterally turned end disposed in said opening.
17. In a device of the class described, the combination of a tank having a fuel supply connection; a stem disposed in said tank, and provided with passages connecting said tank with a source of suction and the at-

mosphere respectively; valve mechanism for controlling said passages, said stem having also a passage connecting said tank with the carbureter; a non-return valve disposed in said last-named passage; and an atmospheric vent in said tank, of much smaller cross section than the passage connecting said tank with the source of suction.

18. In a device of the class described, the combination of a tank, continuously open to the atmosphere; a fuel supply connection; a stem disposed in said tank, provided with passages connecting said tank with the atmosphere and with a source of suction respectively; valve means for controlling said passages; and a connection between

said tank and the carbureter provided with a non-return valve therein.

19. In a device of the class described, the combination of a tank, continuously open to the atmosphere, and provided with a fuel supply connection; connections between said tank and the atmosphere and a source of suction respectively; float operated valve means for intermittently controlling said last named connections; and a passage connecting said tank with the carbureter, provided with a non-return valve therein.

In testimony whereof we affix our signatures.

HERMAN R. SAXON.
GEORGE GANZERT.
